UNITED STATES PATENT OFFICE.

ORLANDO W. NORCROSS, OF WORCESTER, MASSACHUSETTS.

FIRE-PROOF FLOOR.

SPECIFICATION forming part of Letters Patent No. 417,500, dated December 17, 1889.

Application filed February 4, 1889. Serial No. 298,604. (No model.)

To all whom it may concern:

Be it known that I, ORLANDO W. NORCROSS, of the city and county of Worcester, and State of Massachusetts, have invented certain new and useful Improvements in Fire-Proof Floors; and I do hereby declare that the following is a full, clear, and exact description thereof, reference being had to the accompanying drawings, forming a part of this specification, 10 and in which—

Figure 1 represents a vertical section through part of a floor embodying my improvements, taken lengthwise of the supporting beams or joists. Fig. 2 is a similar section taken cross-wise of said beams or joists. Fig. 3 represents a modification of the construction shown at the bottom of Fig. 1; and Fig. 4 is a perspective view, upon an enlarged scale, of one of the wire fasteners for securing the ceiling-lathing strips, hereinafter described, to the bottoms of the beams or joists.

My invention relates more particularly to floors supported by iron beams employed in the construction of large and what are commonly termed "fire-proof" buildings, but is also applicable to other classes of buildings. The object thereof is to produce a floor which shall be fire-proof, (aside from the usual planking or flooring on top,) as well as light and 30 strong, and of cheap construction.

It consists in the combination of various old elements, as hereinafter described, whereby said results may be attained.

Following is a detailed description of my 35 said invention with reference to the accompanying drawings.

The parts marked A A represent two ordinary iron floor beams, which may be fastened in position to support the other parts of the 40 floor in the usual way. Upon the tops of said beams are in practice laid over the whole surface of the floor a covering of corrugated sheet-iron B, with the various sections preferably overlapping one another at the joints, as indicated at a in Fig. 1. The lining-floor C, 45 preferably of plank, is laid on top of said corrugated iron, and upon said plank is in turn laid the ordinary top flooring D, as usual.

By employing the corrugated iron over the 50 iron beams, as aforesaid, the planking or lining floor may be laid in any desired direction

without regard to the position of the floor-beams, said corrugated iron producing a firm and rigid support for the flooring at all points, even when the beams are placed apart at a 55 considerably greater distance than usual. The planking may be fastened down by passing suitable nails through the same and the corrugated iron; but it is not deemed necessary to do so to properly hold it in position. 60 In case of employing such fastenings wrought-iron nails would be preferable, as they may be driven against the top of the iron beams and clinched under the corrugated sheet-iron.

If desired, a layer E, of paper or some kind 65 of fire-proof material, may be placed between the lining and top flooring, and thus serve as an additional safeguard against fire.

To the bottoms of the iron beams are fastened wood-lathing strips F, of proper shape 70 and thickness to receive and hold the plaster G, said strips being fastened to the flanges of the beams by means of suitable wire nails or other fastening devices H, adapted to be driven into the strips and hooked over the beams, as 75 best shown in Fig. 2. Nails made from wire of substantially the shape shown in Fig. 4 are preferable for the above purpose. Wooden strips about seven-eighths of an inch thick, eight to twelve inches wide, and provided 80 with a series of dovetail-shaped grooves b, as shown in Fig. 1, are also preferable to plaster upon; but I do not limit myself thereto, as other shapes may be employed to effect the same result, an instance of which is shown in 85 Fig. 3 in said modified construction, narrower strips being shown with square grooves c c at the sides, and a dovetail-shaped groove b at the center underneath. When the shape first described is used, it is preferable to provide 90 the strips in line with each groove with a series of vertical air-vents d to allow the air to pass out, and thus permit the plaster to be pressed up and completely fill said grooves.

If desired, additional protection against fire 95 may be obtained by plastering between the beams over the top surfaces of the lathing-strips, as is indicated in Fig. 3, as well as upon the bottom thereof. Said provision is not essential, however, and I do not limit myself thereto.

It is a well-known and established fact that

wood coated with mortar or plaster is one of the best and most effectual barriers against the progress of fire, this fact having been demonstrated in many practical instances where 5 wood-work thus protected has been found after disastrous fires in a comparatively unimpaired state. For this reason I have adopted this old and well-known construction as a part of my improved combination.

- 10 A floor constructed in the manner hereinbefore specified, it will be obvious, would be absolutely fire-proof and serve as an effectual fire-stop between one story and another, except in case of a general conflagration, no 15 wood-work being directly exposed, except the top flooring, and in case of said floor burning away the downward course of the fire would be stopped by the layer of corrugated sheet metal, thus resulting in but trifling damage 20 to the building. Then again by dispensing with the usual fire-brick, earthenware, and similar arches between the iron beams commonly employed in the construction of a fire-proof floor or roof, I find I am enabled to reduce 25 the weight of such floors thirty-five pounds per square foot, the corrugated metal

serving not only as a protection against fire, but also as a support for said floors. Furthermore, I am also enabled to place the iron beams considerably farther apart with safety, 30 and in consequence thereof and the other provisions to materially reduce the cost of such fire-proof floors.

It will be understood that the invention is not confined to floors, but may be employed 35 as well in the construction of roofs and other places requiring a like protection.

Having described said invention, what I claim as new, and desire to secure by Letters Patent, is—

40 The girders A, in combination with the corrugated sheet metal B, the usual wood flooring, the lathing F, fastened to the bottoms of the girders by suitable clamps H, and plaster G, the sheet metal B being laid on top of 45 said girders under the wood flooring, substantially as and for the purpose set forth.

ORLANDO W. NORCROSS.
